(57) **CLAIM**

The ornamental design for a shopping cart seat cover for pets, as shown and described.

DESCRIPTION

FIG. 1 is a perspective view of a shopping cart seat cover for pets showing my new design;

FIG. 2 is another perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a perspective view of a second embodiment of FIG. 1 shown with alternate environment;

FIG. 10 is another perspective view of FIG. 9;

FIG. 11 is a top plan view of FIG. 9;

FIG. 12 is a bottom plan view of FIG. 9;

FIG. 13 is a front elevational view of FIG. 9;

FIG. 14 is a rear elevational view of FIG. 9;

FIG. 15 is a right side elevational view of FIG. 9; and,

FIG. 16 is a left side elevational view of FIG. 9.

The broken lines in FIGS. 1, 9 and 10 are for illustrative purposes only and form no part of the claimed design.
